COTTON PICKER'S TRUCK.

APPLICATION FILED DEO. 6, 1906.

UNITED STATES PATENT OFFICE.

ALEXANDER SANDERS, CLARENCE M. REBMAN, AND BENJAMIN H. SANDERS, OF OKEMAH,
INDIAN TERRITORY.

COTTON-PICKER'S TRUCK.

No. 871,893.

Specification of Letters Patent.

Patented Nov. 26, 1907.

Application filed December 6, 1906. Serial No. 346,664.

To all whom it may concern:

Be it known that we, ALEXANDER SANDERS, CLARENCE M. REBMAN, and BENJAMIN H. SANDERS, citizens of the United States, residing at Okemah, Creek Nation, Indian Territory, have invented certain new and useful Improvements in Cotton-Pickers' Trucks, of which the following is a specification.

10 In picking cotton, the operators use a long narrow sack and usually drag the sack over the ground between the rows of cotton plants, and as the sacks are filled, they become more burdensome, manifestly, and soon wear out 15 by the abrasive action due to contact with the ground.

The primary object of our invention is to provide a truck for cotton pickers' use, which will be of simple, and durable construction, 20 and which will conform itself to the uneven condition of ground over which it is trundled or drawn by the sack between the rows of cotton plants, so as to facilitate and render more easy the picking of cotton and to 25 alleviate to some degree the tiresome effects of the operation.

For a full understanding of the invention and the merits thereof and also to acquire a knowledge of the details of construction of 30 the means for effecting the result, reference is to be had to the following description and accompanying drawings, in which:

Figure 1 is a perspective view of one form of our improved cotton picker's truck, the 35 picker's bag being shown in full lines at its front end, and at its rear end in dotted lines in operative connection with the truck; Fig. 2 is a top plan view of the truck; Fig. 3 is a transverse sectional view; Fig. 4 is a top plan 40 view illustrating a modification; and, Fig. 5 is a detail view illustrating a form of bracket employed for the journaling of rollers.

Corresponding and like parts are referred to in the following description and indicated 45 in all the views of the drawings by the same reference characters.

Our improved cotton picker's truck is transversely foldable, and in that embodiment of the invention illustrated in Fig. 1, 50 the body portion of the truck is composed of an intermediate section 1 and two side sections 2 and 3, said sections being foldably connected together by means of strap hinges or similar devices, and the two side sections 5 are preferably of a combined width equal to

the intermediate section 1 so as to fold upon the outer face thereof.

To the lower face of the intermediate section 1 front and rear reinforcing plates 4 are secured and each of said plates carries a 60 pair of strap brackets 5 that are crimped intermediate of their ends as indicated at 6 so as to form journal bearings for the pintles or axles of the front and rear rollers 7. These rollers 7 are preferably beveled at their 65 ends as indicated at 8 and are intended to travel in the furrows between the rows of growing plants. The height of the truck is such as to in no wise interfere with the branches of the plants. Side rollers 9 are 70 journaled between pairs of similar strap brackets on the normally lower sides or faces of the two side sections 2 and 3, being preferably located about midway of the ends of the said sections, and as the truck is drawn 75 along, these side sections manifestly may swing up to a greater or less degree, so as to assume a somewhat inclined position, with their rollers 9 riding along the sides of the furrow. A clevis 10 is secured to the front 80 end of the truck, and a snap-hook 11 may be provided so as to connect said clevis detachably with a ring 12 sewed or otherwise secured to the cotton picker's sack 13.

In practical operation, the strap of the 85 sack is placed over the shoulder of the operator and the sack at its rear end is supported upon the truck. As the cotton picker proceeds between the rows of plants and picks the cotton, the truck will support the sack 90 and facilitate the free movements of the picker, as it is obvious that the pivotal or hinged connection between the sections and the consequent tilting or inclination of the 95 said sections, will form a pocket for the sack upon the truck and prevent it from slipping off of the same at either side.

In that form of the invention illustrated in Fig. 4, the body portion of the truck is constructed in two equal sections that are 100 hinged together at their meeting side edges as shown, and each section may be formed of longitudinally spaced slats 16 secured together by front, rear, and intermediate cross slats 17, and either or both ends of the truck 105 may be tapered. This embodiment of the truck is provided with front and rear rollers 18 that are arranged in pairs, one roller of each pair being journaled in the respective sections and in strap brackets 19 similar to 110

the strap brackets 5 above described. This truck is also provided with side rollers 20, one for each section 15 and preferably mounted at about midway of the length of the truck, as shown. This form of truck is similar in general operation to the form of truck first described, as it is obvious that the two sections will accommodate themselves to the different or varying uneven condition of the ground over which the rollers travel, and the front and rear rollers travel over the base of the furrow and the side rollers travel along the sides of the two adjacent ridges. In this construction also, it is evident that the sack will be securely held on the truck, as the two sections dip towards the middle. The truck is designed to be secured to the sack in any suitable manner, such as that described with respect to the other embodiment of our invention and preferably the draft is applied at a point about one foot back of the end of the truck.

From the foregoing description in connection with the accompanying drawing, it will be seen that we have provided a very simple and efficient construction of truck to support the sack of a cotton picker and one which will alleviate to a considerable extent the burden of drawing the sack along as it is being filled with cotton, while at the same time the provision of a truck of this char-

acter will increase the life of the sack as it keeps it from direct contact with the ground.

Whenever it is desired to carry the truck to and from the field, this may be readily accomplished by folding the parts together.

Having thus described the invention, what is claimed as new is:

1. A cotton picker's truck comprising a plurality of longitudinal sections having a hinged connection and swinging freely with relation to each other, the sides being adapted to tilt upwardly to accommodate the truck to the furrow, and rollers applied to the various sections. 45

2. A cotton picker's truck comprising a plurality of longitudinal sections having a hinged connection and swinging freely with relation to each other whereby the sides are tilted upwardly to accomodate the truck 50 to the furrow, front and rear rollers for the said sections, and side rollers mounted upon the sections between the front and rear rollers.

In testimony whereof we affix our signatures in presence of two witnesses.

ALEXANDER SANDERS. [L. S.]
CLARENCE M. REBMAN. [L. S.]
BENJAMIN H. SANDERS. [L. S.]
